ADJUSTABLE PIVOT MEMBER FOR
SWINGING DOORS

Ernest R. Schroeder, Hawthorne, N. J., assignor
to American Car and Foundry Company, New
York, N. Y., a corporation of New Jersey

Application January 6, 1939, Serial No. 249,607

5 Claims. (Cl. 16—131)

This invention relates in general to improvements in the pivot mounting of doors and in particular to universally adjustable pivots for use in positioning and supporting folding or swinging doors, the present application being a continuation in part of my application Serial No. 143,700, filed May 20, 1937.

The drawing shows the invention applied to the positioning or mounting of folding doors for wardrobes, but it is to be understood that this is merely by way of example as, obviously, the invention is applicable to the mounting of any folding door. In the past wardrobe doors have been hung by means of rigidly mounted pivots which were not readily adjustable. These rigidly pivoted doors became very troublesome and difficult to maintain in proper operative relation after being in use a short time due to changes in the door as well as the floor or wardrobe structure itself, and adjustment of the doors involved a great amount of work. The present invention is designed to overcome the disadvantages of this rigid type of door mounting.

An object of the present invention is the provision of a pivot member for wardrobe doors which may be rigidly secured to the floor of a building or wardrobe structure with the pivot axis of the member adjustably mounted in order to permit inaccuracies of position of the doors to be corrected.

Another object of this invention is the provision of a pivot member in which the pivot axis may be readily shifted in order to compensate for changes in the building or wardrobe structure.

Still another object of the invention is the provision of adjustable means for pivotally supporting a door supporting rod in such a manner that its axis is properly maintained.

These and other objects of the invention will be apparent to persons skilled in the art from a study of the following description and accompanying drawing in which:

Figure 1 is a front elevational view of a portion of a wardrobe showing the application of the invention to one form of door mounting;

Fig. 2 is a sectional view of the improved pivot member;

Fig. 3 is a plan view of the improved pivot member shown in Fig. 2, with portions thereof broken away to more clearly disclose the construction, and

Fig. 4 is an elevational view similar to Fig. 1, but showing the use of the invention with another type of door mounting.

Referring now more particularly to the drawing, as shown in Fig. 1, the wardrobe structure is provided with side walls A, rear wall B and doors C carried for swinging movement by arms or brackets 2 connected at one end, as at 3, to the doors and secured to pivot rod 4, which latter in turn is supported by the improved pivot member D secured to the floor E of a building. The side walls A rest directly upon the floor E, while the rear wall B and doors C, in the instance shown, are raised above the floor to provide an air space below the wardrobe for the purpose of ventilation. The wardrobe is preferably built into a recess in the wall of a room or building, but may also be installed in any other suitable location where sufficient space or clearance is available. There may be as many doors, each with its individual pivot assembly, as desired, depending upon the size of the wardrobe, but as they are substantially identical, only one thereof is shown and described.

Referring now to Fig. 2, the improved pivot member consists of a bottom casting or bearing plate indicated generally at 6, angle shaped in cross section to provide a base portion 8 and an upwardly extending annular side portion 10 through which latter screws or other securing means 12 extend, thus securing the bearing plate to the floor E. There are preferably two of these pivot members provided, one at the bottom and one at the top of the wardrobe structure joined by the pivot rod 4, but since these pivot members are substantially identical, a description of one will suffice. The upper surface of portion 8 constitutes a bearing surface 13, the purpose of which is hereinafter pointed out. The bearing plate 6 is provided with a central opening 14 of sufficient diameter to accommodate the end of the pivot rod 4 in case the rod is longer than the distance between the opposed bearing plates. 40 The upstanding edge or flange 10 of the bearing plate or cup is drilled and tapped at a plurality of points to receive adjusting screws 16. These screws are preferably made with a rounded or ball-shaped head portion 18. Bearing pivot member 20 is formed with an annular base portion 22 which rests upon the bearing surface 13 of the bearing plate 6, while the peripheral surface has an arcuate groove 24 cut therein to receive the ball-headed ends of the adjusting 50 screws, thus permitting movement of the bearing pivot member 20 while preventing vertical shifting thereof. The bearing pivot member or adjusting bearing block is also provided with an upstanding cylindrical projection 26 which is 55

interiorly threaded to receive the respective end of the pivot rod 4 previously referred to. In order to protect the bearing member as well as to give a finished appearance to the assembly 5 a cover member or cap 28 is provided having a downwardly extending flange 30 and a horizontally extending flange 32 adapted to receive securing means such as countersunk screw bolts 34 which extend into the tapped openings in the 10 bearing plate or cup 6. The cap 28 is of sufficient size to provide a considerable clearance between the downwardly extending flange 30 and the edges of the bearing plate, all as clearly shown in Fig. 2.

15 In securing the pivot member to the building or wardrobe structure, the lower bearing plate or cup 6 is secured to the floor E in approximately the correct position; that is, with the center of the cup coinciding as nearly as possible with the 20 axis of the intended pivot. With the bearing plate 6 secured in position with the fasteners 12, as illustrated in Fig. 2, the bearing pivot member 20, including the upstanding projection 26, is arranged in the cup and seats on the upper surface 25 of the base portion 8. During this preliminary assembly the screws 16 will be in their withdrawn position leaving the interior of the bearing cup unobstructed, but after the bearing pivot member 20 is in position, these adjusting 30 screws are screwed inwardly to engage the pivot member, thus retaining it in position and permitting shifting thereof to such a location within the cup that the pivot axis of the rod 4 coincides with the correct pivot axis for the door. After the 35 adjustable pivot member 20 has been properly located, the protecting cap 28 is placed in position, as illustrated in Fig. 2, and the securing screws 34 inserted, thus securing the parts in position. With the bearing plate 6, pivot member 28 and cap 28 arranged as just described, the 40 pivot rod 4 is placed in position and the lower threaded end of said rod 4 threadedly secured within the pivot member 20 and its associated projection 26. Following this arrangement, the door C is then connected with the rod 4 by means 45 of the arms or brackets 2. It will be seen that with this assembly should the door or building structure shift in any way due to sagging or shrinkage, the pivot axis may be again returned to its proper position merely by removing the protecting cap 28 and shifting the adjusting screws, thus moving the pivot member or adjustable bearing block to its correct position without in any way disturbing the door structure.

50 It will be seen that the adjustable pivot member just described may be used with various types of wardrobe door mountings; that shown in Fig. 1 being merely illustrative of one type. Another form of mounting for the wardrobe doors is shown in Fig. 4 in which the pivot rod 4 is connected to the door C by suitable bearings 36 and has its end portions offset as at 38 and arranged in the pivot member 20 in a manner similar to that shown in Fig. 1.

While the invention has been described more or less in detail it is obvious that various modifications and rearrangements of parts will be possible and all such modifications and rearrangements of parts are contemplated as come within the scope of the following claims.

What is claimed is:

1. An adjustable pivot assembly comprising, a rigid bearing plate, said plate being angle-shaped in cross section and having a base portion providing a support, a pivot member having bearing on said support, a pivot rod carried by said pivot member, and means carried by said bearing plate and engageable with said pivot member for shiftably adjusting the member and rod in any direction at right angles to the pivot rod axis.

2. An adjustable pivot assembly comprising, a rigid bearing plate, said plate being angle-shaped in cross section and having a flat base portion adapted to support a pivot member, a pivot member movably supported by said base portion and formed with a groove therein, a pivot rod carried by the pivot member, and means carried by said plate and engaging said groove to restrain the pivot member against vertical movement relative to said plate but permitting rotation of said pivot member.

3. An adjustable pivot assembly comprising, a rigid bearing plate, said plate being angle-shaped in cross section with a flat base supporting portion and an annular wall portion surrounding the same, a disc-like pivot member movably supported on said base portion and formed with a peripheral groove, and means carried by said wall portion and engageable with said groove for shiftably adjusting the position of said pivot member, said means comprising a plurality of ball-ended screw bolts with the ball end normally positioned within the groove to retain the pivot member in its adjusted position against bodily movement in any direction.

4. An adjustable pivot assembly comprising, a rigid bearing plate, said plate being angle-shaped in cross section and having a base portion providing a support, a pivot member movably supported on said base portion, a pivot rod carried by said pivot member, means carried by said bearing plate and engageable with said pivot member for shiftably adjusting the member and rod in any direction at right angles to the pivot rod axis, and a cap overlapping and projecting said bearing plate and pivot member.

5. An adjustable pivot assembly comprising, a rigid bearing plate, said plate being angle-shaped in cross section with a flat base supporting portion and an annular wall portion surrounding the same, a disc-like pivot member movably supported on said base portion and formed with a peripheral groove, and means carried by said wall portion and engageable within the groove for shiftably adjusting the position of said pivot member.

ERNEST R. SCHROEDER.
